ABSTRACT OF THE DISCLOSURE

There is disclosed herein display means for merchandising a replacement tool handle comprising a handle, wedge means attached to the handle, and a U-shaped suspension member inserted in the upper end of the handle.

This invention relates to means for displaying merchandise and relates more particularly to means for merchandising replacement handles for hammers, axes, hatchets and similar hand tools.

When displaying replacement tool handles of the type referred to, it is desirable that the handles be grouped according to size and shape whereby the customer can conveniently make a selection of the handle suited to his particular need. It is also important that he be able to remove the handle easily from the display means for the purpose of examining it, checking its gripping characteristics, and otherwise satisfying himself of the correctness of his choice. Each replacement handle preferably includes wedge means of the correct size whereby each unit displayed constitutes a complete kit for repairing a hand tool, it being unnecessary for the customer to separately select and purchase the wedge means.

The general object of this invention is to provide merchandise display means adapted to display replacement tool handles in groups according to size and shape.

Another object of this invention is to provide such display means wherein the handles are easily removable for examination by the customer.

Still another object is to provide display means as set forth above wherein simple suspension means is provided for suspending a plurality of handles of like size and shape from a generally horizontally disposed rod carried by a display rack.

Yet another object of this invention is to provide suspension means as set forth above which is simple and economic to manufacture, easily attached to the handles, and highly reliable in use.

Another object of the invention is to provide, in display means as set forth above, a generally U-shaped suspension member having leg portions adapted to be driven into the upper end of a wooden handle with a minimum tendency to split or crack the wood.

A still further object is to provide display means of the above type providing a customer with a selection of handle kits each of which comprises a handle and wedge means of the correct size for mounting said handle to a tool.

Other objects of the invention and the invention itself are disclosed in the following specification and accompanying drawings:

FIGURE 1 is a perspective view of display means of this invention including a replacement tool handle and suspension means therefor:

FIGURE 2 is a side plan view showing a plurality of suspended tool handles;

FIGURE 3 is an enlarged detail in elevation of the upper end portion of the tool handle shown in FIGURE 1;

FIGURE 4 is a view of the upper end portion of FIGURE 3 as seen from the right-hand side thereof:

2

FIGURE 5 is an enlarged elevation of a suspension member as seen from one side, portions thereof being broken away;

FIGURE 6 is an elevation of the suspension member of FIGURE 5 as seen from the other side thereof; and

FIGURE 7 is a view of the suspension member of FIGURES 5 and 6 as seen from the right-hand side of FIGURE 6.

Referring now to the drawings in all of which like parts are designated by like reference numerals, FIGURE 1 shows the entire display means comprising a tool handle 10 having a lowermost grip portion 11 and an uppermost shank 12. In the embodiment of the invention as herein illustrated, the tool handle 10 is adapted for use with an ordinary carpenter's hammer and is made of wood. However, it will be understood that the present invention is adapted for use in connection with other types of tool handles which may be made of other suitable materials.

20 The uppermost end portion of the shank 12 is provided with an upwardly open, transverse slot 13 which extends downwardly a substantial distance into said shank. As will be readily understood by those familiar with the art, the shank 12 is adapted to project upwardly through the eye of the tool head (not herein illustrated) after 25 which wedge means are driven into the transverse slot 13 to expand the shank 12 and cause it to have a tight frictional engagement with the tool head. To insure that the purchaser of the replacement handle is provided with the proper wedge means for the size handle being used, said 30 replacement handle has wedge means 14 removably attached to the shank 12 by any suitable means such as tape 15. In the present instance, the wedge means 14 comprise a tapered wooden wedge 16 and a smaller tapered metal wedge 17.

35 The upper end portion of the shank 12 carries an upwardly projecting suspension member 20 which is generally of inverted U-shaped form having downwardly projecting legs 21a and 21b which are driven into the upper end of the shank 12 alongside of the transverse slot 13. Said suspension member affords an eye adapted to loosely fit over a substantially horizontal rod 22 which is carried by a support member 23 of a display rack of any suitable design.

45 The suspension member 20 is shown in detail in FIGURES 5-7 and comprises an upwardly arched central portion 24 and the aforementioned downwardly directed legs 21a and 21b. As herein disclosed, said suspension member is formed from a single length of steel wire, and the downwardly directed end portions of said legs are sharpened to provide penetrating points 25a and 25b. As shown in FIGURE 5, the leg 21a has a front facing tapered surface 26a and a side tapered surface 27a, the side tapered surface being disposed on the outer side of 50 said leg. As shown in FIGURE 6, the leg 21b is provided with a front facing tapered surface 26b and a side tapered surface 27b, the surface 27b being disposed on the inner side of said leg and generally parallel with the surface 27a. As a result of the positioning of the aforementioned tapers, the lower end portions of the legs 21a and 21b 55 are tapered laterally in the same direction as seen in the elevations of FIGURES 5 and 6 and are tapered outwardly in opposite directions as viewed in FIGURE 7.

In preparing the tool handle 10 for shipment and eventual display, said handles are provided with wedge means 14 of the correct side and type by detachably taping the same to the shank portion 12 whereby a complete kit is provided for repairing the tool handle. A suspension member 20 is driven into the upper end of the handle whereby said handle can readily be mounted for display upon a rod 22. In use of the replacement handle, the purchaser simply removes the suspension member 20, inserts the shank portion 12 into the tool socket and then drives

the wedge means 14 into the slot 13 of the handle. The suspension members 20 may be provided in different sizes for suspending replacement handles 10 of different sizes and weights. It has been found that the particular tapering of the lower end portion of the legs 21a and 21b affords easy penetration of the upper end of the handle with a minimal tendency to split or fracture the handle. The penetrating legs 21a and 21b frictionally engage the upper end portion of the handle with sufficient force to obviate any tendency for the handles to drop off the display due to separation from the suspension means even when subjected to substantial amounts of handling and replacement on the rods 22 by retailers and customers.

What is claimed is:

1. Detachable display means for merchandising an elongated replacement handle, said handle adapted to be used as an article of display and subsequently as a replacement handle for the work head of a tool, said display means comprising the said elongated handle; a support member having a rod projecting outwardly therefrom; a suspension member of inverted U-shape form having downwardly projecting sharpened legs; said legs each having a front facing tapered surface and a side tapered surface, one of said legs having its side tapered surface on the outer side of said leg and the opposite leg having its side tapered surface on the inner side of said leg substantially

5 parallel with the side tapered surface on said other leg, the lower end portions of each of said legs being driven into one end of said handle with a substantial portion of the inverted U-shape projecting above said one end of said handle and said suspension member being threaded upon said rod whereby said handle is suspended from the said rod for display thereof.

10 2. Display means as set forth in claim 1: said handle having a transverse slot in one end thereof adapted to to receive wedge means for securing said handle to the work head of a tool; and wedge means for inserting into said slot detachably carried by said handle for purchase therewith.

15 3. Display means as set forth in claim 1: said handle having a shank portion at said one end thereof; said shank portion having a transverse slot therein adapted to receive wedge means for securing said handle to the work head of a tool; and wedge means of the correct size and type for use with said handle detachably carried by said shank portion.
